PHOTOENGRAVING OR THE LIKE

Harley C. Alger, Chicago, Ill.

Application July 18, 1942, Serial No. 451,478

3 Claims.

(Cl. 95—81)

This invention relates to the art of photo-engraving, and more particularly to the screens which are used to make half-tone dot positives by what is commonly known as the "Contact Method" and to the use of such screens to produce a positive suitable for use in making intaglio, photogravure printing plates or cylinders.

One of the objects of this invention is to produce a screen for use in making a positive which will have a half-tone dot formation in the lighter tone areas and a gravure dot formation in the denser tone areas.

Another object of the invention is the production of a screen adapted to produce such a positive by contact with the photographic material from which the positive is to be made.

A further object is the production of a screen which may be used to produce a positive having so-called "gravure screen lines" therein which eliminates the step known as "Carbon tissue screening," in making gravure plates or cylinders.

Another object is to produce a screen which may be used to make such a positive which in turn may be used to produce an intaglio image on the surface of a plate or cylinder of such character that the image will not easily wear away during the operation of printing, thus giving long life to such plate or cylinder.

Another object of the invention is to provide an improved method in the art of photo-engraving particularly for producing an improved intaglio printing plate or cylinder.

Other objects and advantages will appear more fully from the following description taken in connection with the accompanying drawing in which

Fig. 1 is a fragmentary view of one form of screen made in accordance with this invention and adapted for carrying out my improved method;

Fig. 2 is a fragmentary view of a modified form of screen made in accordance with this invention;

Fig. 3 is an illustration showing a positive in the form of a tone scale extending from light to dark tones made in accordance with this invention, using the screen shown in Fig. 1;

Fig. 4 is a view similar to Fig. 3 showing a positive also in the form of a tone scale extending from light to dark tones made in accordance with this invention, using the screen shown in Fig. 2.

In gravure printing, many attempts have been made to produce a positive which could be used to make an intaglio printing plate or cylinder which would have a half-tone image in which the various tones are brought out by virtue of varying the size of the dots or wells etched into

the surface and making them of substantial uniform depth, instead of the conventional gravure dot formation in which the various tones are brought out by virtue of dots of varying depth but of substantially uniform area.

One of the disadvantages encountered in so doing has been that the half-tone dot formation cannot be carried further than a semi-tone or the well known checkerboard formation when considering a tone scale extending from light to dark tones, it being necessary to leave the remaining areas unetched or surface high throughout the darker tone areas in order to support the doctor blade. This blade is used to remove surface ink from the printing plate or cylinder during the process of printing. This results in the lowering of the quality well recognized in the art of gravure printing because the tone gradation of such an image does not extend completely to a dark solid but stops far short of this point.

In accordance with this invention, I have eliminated this disadvantage by producing a screen with resultant positive which may be used for making a plate or cylinder printing surface having a half-tone dot image in the highlight areas and also having a gravure dot image in the denser tones, thus extending the tone range of the image completely to a solid dark tone as is common in ordinary gravure printing.

In the attempts heretofore made to produce such a positive, it has been the practice to do the work in a camera using the Levy half-tone screen which is well known in the art. This operation takes considerable time and the use of a camera adds to the cost of positives made by such a method.

In accordance with my invention, considerable time is saved and the cost of the positives is reduced for the reason that the positives can be made quickly in a simple vacuum printing frame by the contact method.

Ordinarily in making a gravure plate or cylinder, a transparent positive image is made in continuous tone uninterrupted by any dot formation. A gravure screen having transparent screen lines and opaque square dots is printed by light in a vacuum printing frame on a sheet of carbon tissue paper which has been sensitized with potassium dichromate; next the continuous tone positive is printed by light in a vacuum printing frame on the same sheet of screened carbon tissue paper. Subsequently the carbon tissue is laid on a copper plate or cylinder which receives the image printed from the screen and positive and which is finally etched to produce a gravure printing

plate or cylinder as is well known in the art. The ordinary gravure screen is one having clear transparent lines surrounding opaque dots or squares, while the "grained" gravure screen is one having irregular transparent lines substantially surrounding irregular opaque dots or areas. In either case, the clear lines permit the surface of the carbon tissue to be hardened and these screen lines correspond to the surface-high lines of the finished gravure plate or cylinder which support the doctor blade during the operation of printing.

As shown in Fig. 1 of the accompanying drawing, the screen 6 is provided with a plurality of vignetted dots 7 or dots having borders that are shaded off gradually and which may be equally spaced in rows A, A and B, B formed on any convenient transparent material such as glass, photographic dry plates or films, as a supporting base. Each dot has a center or core of dense tone with tone gradually reducing in density outwardly from its center reaching a density of practically zero only at the center point at the crossing of the diagonals of each set of four dots or at the center of the areas defined by any four dots. Dense tone lines or bands of solid color 10 are formed running through each row of dots at least in one direction.

Figure 2 shows a modified form of the invention in which the screen 9 is provided with dots 10 formed and arranged in a similar manner to the dots shown in Fig. 1. Dense lines 11 or solid lines of definite formation and substantially uniform width pass through the dots in one direction as shown and other similar lines 12 pass through the dots at right angles to the lines 11.

The screen may be made by preparing a suitable drawing of larger scale than the finished screen and photographing the drawing on a dry plate or film at the same time reducing so that there will be approximately one hundred and fifty to two hundred dots per linear inch. Coarser or finer dot spacing may be made if desired.

Or the screen may be made in the camera by using the Levy screen set close to the dry plate or film upon which the dots and lines are to be formed. In this case, the dots are formed first by setting the distance of the Levy screen from the plate or film so that small dots the size of the core desired, will be formed on the plate and then partially exposing by reflected light to form the cores of each dot. Next the screen distance is altered a small amount so that larger dots are formed, each having an area a trifle larger than the size of the core first formed, again by partial exposure. This process is repeated several times until the dots are increased in size until they overlap and the unexposed areas are only small clear spots at the points where the diagonal lines from the centers of each four dots cross each other. Then the lines are formed by placing a suitable aperture in the lens chamber of the camera and again making a partial exposure. In the case of the single set of parallel lines on the screen as shown in Fig. 1, the aperture is in the form of a narrow slit; while in the screen shown in Fig. 2, which has two sets of parallel lines at right angles to each other, the aperture is in the form of a thin line Maltese cross. After these exposures, the plate is developed, fixed and washed, and a screen having dense tone lines 70 with dots positioned thereon, each dot having a dense center or core with the tone gradually decreasing in density outwardly from its center, is produced.

It would be found that operators skilled in the

use of the Levy half-tone screen can readily produce a screen like the one shown in Fig. 1 or the one shown in Fig. 2 by this method.

After the screen is made, it is to be noted that the image dot 13, that is the portion of the screen that makes the image dot of the positive, is the space having a clear center at the crossing point of the diagonals extending from each set of four dense tone dots; this image dot of the screen having a center with a density of practically zero and with gradually increasing density extending outwardly from its center until it meets the dense tone lines of the screen.

The use of the screen in making positives now becomes a relatively simple matter. The negative made from the copy which it is desired to reproduce, is placed against the glass of a vacuum printing frame, the screen is placed in contact with the negative, a suitable dry plate or film is placed in contact with the screen, the frame is closed and the dry plate is exposed to suitable light, usually an arc light, through the negative and screen to produce an image on the dry plate which is brought out by subsequent development in the form of a positive.

Figure 3 shows such a positive 14 which would result by using the screen of Fig. 1 with a negative made with a tone scale as copy, with tones extending from a very light tone at the left, to a full dense tone at the right. The angle of the lines of the positive when a single set of parallel lines are used, should be such that the corresponding lines which are formed on the printing cylinder are at an angle of 20° to 45° with the line of contact of the doctor blade with the cylinder.

The positive 15 shown in Fig. 4 is similar to that shown in Fig. 3 when made with a screen such as shown in Fig. 2. In accordance with this invention, it will be seen that I have produced a screen which carries a vignetted dot formation which forms half tone dots in the positive when printed from a negative by the contact method and that the screen also carries gravure type screen lines running through the vignetted dot formation which gives a gravure dot formation in the darker tones of the positive. From this it is seen that the positive carries all the necessary screen lines and that the operation of screening the carbon tissue is not necessary as the lines will be formed in the carbon tissue from the positive in a single printing of the positive only.

Further, it will be seen that by the use of this screen with its resultant positive having half-tone dots in the lighter tones, a printing plate or cylinder will be made which will have intaglio half-tones dots representing the lighter tones formed in its surface. These dots are relatively smaller than the conventional gravure dots and the area of surface-high metal around the dots is proportionately larger, thus providing a larger surface to support the doctor blade during the operation of printing which gives the image in the surface of the cylinder longer life, all of which is brought about by the use of my improved screen.

While the accompanying drawing is intended to illustrate the invention as fully as possible, it will be noted that the figures are drawn on an enlarged scale as the wells or ink recesses in intaglio printing are usually of exceedingly small dimensions.

While I have shown and described a preferred form of my improved screen, and my improved method in the art of photoengraving, it will be

noted that changes may be made in the form or details of the screen and in the method of operation without departing from the scope of the invention.

What I claim is:

1. A screen for use in photo-engraving comprising a sheet of transparent base material having a plurality of parallel dense tone solid bands, other parallel dense tone solid bands intersecting the first named bands and circular figures at the intersections of the bands having dense centers and fading toward their peripheries said bands being spaced in accordance with half-tone practice and the circular figures extending beyond the bands and intersecting at substantially midway between the bands.

2. A screen adapted to produce a half-tone image by the contact method, having a transparent base and having a set of substantially continuous parallel dense tone lines of substan-

tially uniform width spaced on the order of 100 to 175 per inch and dots formed at uniform intervals on each line, also spaced at approximately 100 to 175 per inch, the dots on one line being tangent to the dots of the adjacent lines, each dot having a dense tone center with the tone gradually decreasing in density outwardly from its center.

3. A screen for the purposes set forth, having a transparent base with parallel dense tone stripes of substantially uniform width and having vigneted dots intersected by said lines, said dots having dense tone centers with the tone gradually decreasing in density toward the outer periphery with the outer peripheries of adjacent dots substantially intersecting each other, said dots and stripes being spaced substantially in accordance with the usual half-tone practice.
